UNITED STATES PATENT OFFICE.

JOHN A. ADELL, OF ORANGE, MASSACHUSETTS.

DOUBLE-RACK JACK.

Application filed June 30, 1927. Serial No. 202,672.

This invention relates to a jack comprising three telescoping parts which are so related that the jack can be lowered to a height about equal to the height of each one of said 5 parts, or to the tallest one, and can be raised automatically to a height nearly equal to the combined height of the three parts, thus increasing the range of a rack jack.

The principal objects of the invention are 10 to provide a construction of this type in which the parts are all raised vertically throughout their whole range of motion, and in which the intermediate part steadies and stabilizes the inner rack, which is the one 15 moving to the greatest height and having the work-rest; to provide the intermediate part in the form of a vertically movable lifting member or guide, itself guided in the stationary frame or casing of the jack; to provide 20 automatic means by which this intermediate member is automatically converted into a part of the rack when the inner rack reaches the limit of its elevation and thereafter moves upwardly by the use of the same 25 pawls or other lifting device and without any change in the manipulation on the part of the operator; to provide this means with a movable rack member set into the back of the outer lifting member and adapted to be held 30 out of range of the lifting apparatus or pawls at all times except when the inner rack is elevated to its limiting position with respect thereto, to provide a construction in 35 which these two telescoping racks constitute the complete rack for the jack and will be continuous and in alignment while the lower one is operating; to provide means by which the inner rack cannot descend while the lower rack section is in engagement with the pawls, 40 but as soon as that is withdrawn, the inner rack will come automatically into operative co-operation with the pawls, so that it will not drop and especially to provide improvements in the details of the automatic mechanism above referred to.

Other objects and advantages of the invention will appear hereinafter.

Reference is to be had to the accompanying drawings, in which

50 Fig. 1 is a side view of a jack constructed in accordance with this invention;

Fig. 2 is a front edge view of the same with the operating handle shown in section;

Fig. 3 is a central sectional view on the

line 3—3 of Fig. 2, showing the parts in the 55 same position with the pawls operating on the upper rack only;

Fig. 4 is a similar view, with parts omitted, showing the movement of the lower rack section into operative position below the upper 60 rack;

Fig. 5 is a view similar to Fig. 3, showing the load raised by the aid of the two rack sections;

Fig. 6 is a horizontal sectional view on the 65 line 6—6 of Fig. 3;

Fig. 7 is a horizontal sectional view on the line 7—7 of Fig. 5;

Fig. 8 is a rear view of the intermediate housing or rack, showing the automatic 70 latching device from the rear; and

Fig. 9 is a rear view of the inner or upper rack.

Over-sized tires have rendered ordinary 75 rack jacks practically useless at the present time for many makes of cars, because they cannot raise a load to a height more than twice the height of the jack when contracted or lowered. This jack is designed to combine the simplicity of the ordinary vertical 80 rack jack with the possibility of extending the jack to a height approximately three times the height of the casing.

In the embodiment of the invention shown 85 herein, the jack is provided with and mounted in a casing 10 of pressed metal having a base 11, also of pressed metal riveted to it, by flanges 12 at the bottom of the casing. This casing is provided with a vertical central passage, shown here as of a generally square 90 shape in cross section, for receiving the parts that will be described. It is also provided with a substantially rectangular hollow projection 13 for a purpose to be described, and on the other side extends out far enough to 95 provide two walls, each having a perforation 14 for receiving the pivot pin 15 of an operating lever 16 which is adapted to receive the handle. This casing is made preferably of a single piece of metal pressed into shape 100 in dies.

In the central vertical passage in the casing is provided a reciprocable lifting member 17 which also is shown as square in cross section but having its front side open toward 105 the operating lever 16. This is provided at the top with a flange 18 surrounding it on the three sides and at one corner with a di-

agonal cross-pin 19 which extends into the interior far enough to form a stop for a purpose to be described.

Also the rear of this member 17 is provided with an opening large enough to receive a movable latch and rack member 20. This rack member is housed in the projecting part 13 of the casing. It is provided on the front with rack teeth 21 and on the rear with a groove 22, in which is located a spring wire 23, preferably secured to this rack member by means of a coil in the wire around a cross pin 24 supported by the rack member. This spring extends beyond the rack member both above it and below it and is secured at its ends in two studs 25 fixedly mounted in the member 17. The tendency of the spring is to force this rack member outwardly and backwardly into the hollow projection 13. The top of the rack member is rounded off at its upper end 26 on the back and the housing 13 is provided with a slanting surface 27 for cooperating with it to force the rack member inwardly, when raised, where it comes into operative position as will appear later. The casing 10 is provided with a slight enlargement above the projection 13 for receiving the upper stud 25 as the rack is raised.

The inner telescoping rack member consists of a piece of pressed metal 30 having a work-rest 31 at the top, rack teeth 32 pressed into it and its operative face inside this member being also of rectangular shape also with the front side omitted; that is, having three walls only. The only other feature of this is a pin 33 adapted to cooperate with the pin 19 previously described.

With this mechanism is used any desired kind of a pawl arrangement cooperating with the lever 16. I have shown here a pair of pawls 35 and 36 with a spring 37, and a setting lever 38 so that this lever can be set in either of the two positions shown to cause the pawl action to raise the racks or lower them.

In the operation of the device, assuming the parts to be in the position with both racks, that is, the members 30 and 17 at the bottom, so that the work-rest 31 rests just above the top of the casing 10, the lever 38 is set as shown in Fig. 3 and the lever 16 is operated. The two pawls 35 and 36 cooperate to raise the rack 30 in the manner well-known in this industry so that it need not be described in detail.

When the rack 30 is raised to a point where the pin 33 engages the pin 19, its further movement upwardly one step will start up the lifting member 17. The result of this is to draw the rack member 20 upwardly with it of course, so that the rounded upper end 26 will engage the inwardly slanting surface 27 and force the parts into the position shown in Fig. 4. It will be seen that this forces the upper end of the rack 21 into the same vertical

plane as the rack teeth 32. Therefore the pawls will immediately commence to act upon this lower lifting member 17 without any intermission or any change in the operation of the lever 16. At this time the rack 30 rests on the top of the rack member 20, and, therefore, the former cannot descend or get released in any way. Thus the load is supported as rigidly as before. As the operation progresses the rack member 20 comes entirely inside the casing and eventually reaches a vertical position as shown in Fig. 5 where it will serve as part of the rack. It will be seen that, while the spring 23 is trying to force this member outwardly away from the pawls, this is prevented by positive means, namely, the inside rear wall of the casing which engages the rear edges of the rack member 20. This member is a little thicker at the center than at the ends which makes the bearing point come half way between the ends and allows a little play which may be needed at times. The rack member 20, however, is still housed within the opening in the member 17 at all times, so that it cannot get out and can support the weight that may come upon it. This weight is transmitted through this member, so it is made strong.

On the lowering of the jack the lever 38 is set in the opposite position as shown in Fig. 1, and then the operation of the lever in the usual way lowers the member 17 through the operation of the pawls on the rack member 20 until this member comes down to its lowermost position. At that time the rack member is free to swing out into the opening in the back of the hollow member 17. The spring 23 tends to pull it out immediately against the resistance due to the fact that the rack 30 is resting upon its top. This is, of course, assisted by the slanting surface 27. Now this rack member no longer supports the rack 30, but the teeth of the latter are acted upon by the pawls in the same way as usual, so that it can be lowered clear down to the bottom with no difficulty whatever, always under the control of the pawls.

This constitutes a simple means for providing a pressed steel jack of the vertical telescoping rack type which will be capable of being expanded to a little less than three times its minimum height; the pawl mechanism does not have to be changed, as any pawl mechanism that will operate satisfactorily on a single rack jack can be used for this one without change; the parts are comparatively simple and of such a nature that they will operate automatically and certainly and in the same way as is usual in rack jacks of this general type, so no new method of operation has to be learned, and the addition to the cost of the ordinary single rack jack is comparatively slight. Another important advantage is that it takes up practically no more room

with the exception of the projection 13 than an ordinary single rack jack.

Although I have illustrated and described only a single form of the invention I am 5 aware of the fact that changes can be made therein by any person skilled in the art without departing from the scope of the invention as expressed in the claims.

Therefore I do not wish to be limited to 10 the exact form shown, but what I do claim is:—

1. In a lifting jack, the combination with a casing having a vertical passage, a lifting member located in said passage and movable 15 up and down therein, and an inner rack movable up and down, of a pawl motion for operating the rack, and a movable rack member movably mounted on the lifting member and movable to a position below the said inner 20 rack and in line therewith so as to be operated on by the pawl mechanism.

2. In a lifting jack, the combination with a base and a casing fixedly mounted thereon, said casing having a vertical passage from 25 the bottom to the top, of a lifting member located in said passage and movable up and down therein, an inner rack member located in the lifting member and movable up and down therein, a pawl motion for operating 30 the rack, a movable rack mounted on the lifting member, and means whereby when the said lifting member is raised to a certain point the rack will be forced forward in the jack to a position below the said rack member and in line therewith so as to be operated 35 on by the pawl mechanism.

3. In a lifting jack, the combination with a casing having a vertical passage therein, of a lower lifting member, a telescoping rack, 40 pawl mechanism for raising and lowering said rack, a rack member movably carried by the lifting member, and means for forcing the rack member inwardly into a position below the rack when the rack is raised just 45 above it, so that the pawl mechanism will engage said rack member and raise the lifting member and the rack.

4. In a lifting jack, the combination with a casing having a vertical passage therein, 50 of an outer lifting member hollow in shape and open at one side, a rack mounted in the lifting member and adapted to be guided up and down therein, pawl mechanism for raising and lowering said rack, a rack member 55 carried by the lifting member, and means for yieldingly forcing the rack member back in the lifting member so as to rest behind the rack, said casing having means for forcing the rack member inwardly into a position below the rack when the rack is raised just above 60 it, so that the pawl mechanism will engage

said rack member and raise the lifting member and the rack.

5. In a lifting jack, the combination of a base, two telescoping lifting members slid- 65 able therein, the upper member having rack teeth, pawl mechanism for engaging in said teeth and raising or lowering the upper member, means whereby when the upper member is raised to a certain point it will pick up the 70 lower member and carry it with it, and means carried by the lower member and adapted to move at that time into alignment with the rack teeth on the upper member and to support said inner member. 75

6. In a lifting jack, the combination of a base, two telescoping lifting members slid- 80 able therein, the outer of said members being U-shaped and the inner member being located within the outer member, the inner member 85 having rack teeth on the front of its rear surface, pawl mechanism projecting into the inner member for engaging in said teeth and raising or lowering the inner member, means whereby when the inner member is raised to 90 a certain point it will pick up the outer member and carry it with it, and means carried by the outer member and adapted to move at that time into vertical alignment with the rack teeth on the inner member and to support said inner member. 95

7. In a lifting jack, the combination with a casing and two telescoping lifting members 100 slideable vertically therein, the inner member having rack teeth thereon, means for 95 engaging the rack teeth and raising and lowering the same, said outer member enclosing the inner member and having an opening through the back, a rack member located in said opening, yielding means for normally holding the rack member back in alignment with the rear wall of the outer member, and means for forcing the rack member, when the outer member is lifted from its original lowermost position, into alignment with the rack 105 teeth on the inner member.

8. In a lifting jack, the combination with a casing and two telescoping lifting members slideable therein, the inner member having rack teeth thereon, means for engaging the 110 rack teeth and raising and lowering the same, said outer member having an opening, a rack member located in said opening, means for normally holding the rack member back in the outer member, and means for forcing the 115 rack member, when the outer member is lifted from its original lowermost position, into alignment with the rack teeth on the inner member.

In testimony whereof I have hereunto af- 120 fixed my signature.

JOHN A. ADELL.
